UNITED STATES PATENT OFFICE.

BENJAMIN S. McCLELLAN, OF CHICAGO, ILLINOIS.

WINDOW-SASH.

1,149,072.

Specification of Letters Patent.

Patented Aug. 3, 1915.

Application filed April 12, 1910. Serial No. 555,107.

To all whom it may concern:

Be it known that I, BENJAMIN S. McCLELLAN, a citizen of the United States, and residing at Chicago, in the county of Cook and State of Illinois, have invented a new and useful Improvement in Window-Sash, of which the following is a complete specification.

Car window sash as heretofore constructed have had their lower inner corners or edges subjected to considerable injury by being jammed or splintered by careless employees while passing car seats or other articles out of the open window. Furthermore where the bottom weather strip for the sash protrudes beyond the outer edge of the sash it becomes injured by the window washers passing their brushes or other cleaning devices across it, and the efficiency of the strip is thereby soon destroyed. And, also, where the strip protrudes outwardly from beneath the bottom of the sash, water will pass by it and enter beneath the sash by reason of its capillary attraction.

The main objects of this invention are to provide a window sash having a metal reinforced lower edge adapted to protect it from injury; to provide a window sash having its bottom rail provided with a detachable protecting bar or member on its inner lower edge which is adapted to protect the edge of the rail from injury, and is also adapted to be replaced by another in case it becomes injured; and to provide a window sash having a bottom weather strip, the outer edge of which terminates inwardly from the outer face of the sash, so that the outer edge of the sash will provide a water drip and prevent the water from creeping beneath the sash.

A specific construction embodying the invention is illustrated in the accompanying drawings, in which:

Figure 1 is a fragmentary, vertical section of a window having a sash embodied in this invention. Fig. 2 is a fragmentary view of the window showing parts in horizontal section and parts in plan view.

In the construction shown, the window sill 1 is inclined downwardly on its upper surface in the usual manner to provide a seat for the sash 2, which is also inclined downwardly and outwardly on its lower edge to conform to the sill.

The bottom of the sash is provided on its lower inner corner with a metal reinforcing

or protecting bar 3, which extends the full length of the bottom rail, and has its edge or back 4 flush with and lying in the plane of the inner face of the sash. The bottom 5 of 60 said bar is inclined to correspond to the inclination of the sill and to seat flatly thereon when the sash is in closed position. The bar 3 is attached to the sash by means of screws 6 extending therethrough and into the sash 65 rail.

Preferably, and as shown, the protecting bar 3 is formed of a channel bar, the width of which is approximately one half the thickness of the sash rail, and the channel of 70 which opens toward the outer side of the sash. The bar is preferably seated in a rabbet provided in the bottom of the sash so that the lower outer edge 7 of the sash extends slightly below the upper flange of the 75 channel and partially closes the opening in the bar.

Carried in the channel is a flexible weather strip 8 of rubber or other suitable material, which extends the full length of the channel and is secured therein by means of the screws 6 passing therethrough. The free edge 9 of the strip projects forwardly from the channel and lies beneath and in close contact with the depending edge 7 of the sash, but terminates inwardly of the outer face of the sash, so that water running down said outer face will drop off onto the sill without touching the strip. The strip 8 is of greater thickness than the distance between the portion or edge 7 of the sash and the top of the sill when the sash is at the lower limit of its movement, so that the sash when closed will slightly compress the strip between the edge 7 of the sash and the sill, 95 as shown more clearly in Fig. 1.

The protecting or reinforcing bar 3 prevents the lower inner edge of the sash from becoming injured by articles hitting the sash and therefore preserves a neat finish for the bottom of the sash. The bar also affords a means for retaining the weather strip in place, and owing to the fact that the bar is seated in the rabbet in the sash it will withstand any ordinary blow without becoming 100 loosened or damaged.

Inasmuch as the weather strip does not protrude forwardly from beneath the sash, it cannot be injured when washing the windows, and it also permits the water to drop 110 directly from the sash to the sill.

While I have shown but one specific em-

bodiment of the invention, it will be understood that many details of the construction shown may be varied or omitted without departing from the scope of the claims.

5 I claim:

1. A window sash, comprising in combination with the lower sash rail, a sheet metal channel member having a vertical back or web and upper and lower parallel flanges, 10 said channel member being applied to the bottom face of said rail with its channel opening outward below the same and toward the outer vertical face of said rail, said web or back extending below the bottom 15 face of said rail from the inner vertical face thereof, said upper flange bearing against the bottom face of said rail and said lower flange extending beneath and spaced vertically below the bottom face of said rail, a 20 flexible flat weather-strip below the bottom face of said rail and having its inner marginal portion inserted in the channel of said channel member; the remaining portion of said strip projecting outward from said 25 flanges and beneath the bottom face of said rail and terminating short of the outer edge of the same; all portions of said weather-strip being entirely below the bottom face of said rail; and said weather-strip and 30 lower flange seating on the sill when the sash is closed and forming the support for said sash, and fastening members inserted through said flanges and the portion of the weather-strip therebetween, for securing

said channel member and weather-strip to 35 said rail.

2. A window sash, comprising in combination with the lower sash rail, a sheet metal member embracing a vertical back or web and a laterally projecting flange, said sheet metal member being applied to said rail with said back or web extending below the bottom face of said rail from the inner vertical face thereof and with said flange extending beneath and spaced vertically below the bottom face of said rail, a flexible flat weather-strip below the bottom face of said rail and having its inner marginal portion overlapped by said flange; the remaining portion of said weather-strip projecting outward from said flange and terminating short of the outer edge of said rail; all portions of said weather-strip being entirely below the bottom face of said rail, and said weather-strip and said flange seating on the sill, 55 when the sash is closed, and forming the support for said sash, and fastening members inserted through said flange and the portion of the weather-strip overlapped thereby, for securing said sheet metal member and weather-strip to said rail.

In testimony whereof I have hereunto subscribed my name in the presence of two witnesses.

BENJAMIN S. McCLELLAN.
